[57] **CLAIM**

The ornamental design for a base of a chair, as shown and described.

DESCRIPTION

FIG. 1 is a left top front perspective view of the new design; FIG. 2 is a left side elevation view thereof; FIG. 3 is a front side elevation view thereof; FIG. 4 is a top plan view thereof; FIG. 5 is a rear side elevation view thereof; and, FIG. 6 is a bottom plan view thereof;

The broken lines illustrate the environmental structure of the base of the chair, and form no part of the claimed design.
